US0D1010662S

(12) **United States Design Patent** (10) **Patent No.:** **US D1,010,662 S**
Pillalamarri et al. (45) **Date of Patent:** **** Jan. 9, 2024**

(54) **DISPLAY SCREEN WITH A GRAPHICAL USER INTERFACE**

(71) Applicant: **INSULET CORPORATION**, Acton, MA (US)

(72) Inventors: **Sandhya Pillalamarri**, Methuen, MA (US); **Jorge Borges**, Billerica, MA (US); **Susan Mercer**, Waltham, MA (US)

(73) Assignee: **INSULET CORPORATION**, Acton, MA (US)

(**) Term: **15 Years**

(21) Appl. No.: **29/713,091**

(22) Filed: **Nov. 13, 2019**

Related U.S. Application Data

(62) Division of application No. 29/597,101, filed on Mar. 14, 2017, now Pat. No. Des. 872,733.

(51) **LOC (14) Cl.** **14-04**

(57) **CLAIM**

The ornamental design for a display screen with a graphical user interface, as shown and described.

DESCRIPTION

FIG. 1 is a front view of a display screen with a graphical user interface showing our new design;
 FIG. 2 is a second embodiment thereof; and,
 FIG. 3 is a third embodiment thereof.

The broken lines showing a display screen, text, and graphic elements illustrate portions of the article, and form no part of the claimed design.

1 Claim, 3 Drawing Sheets
